HOLDING AND DISPENSING DEVICE

Gunnar R. Johner, Portland, Oreg.

Application November 20, 1933, Serial No. 698,818

3 Claims. (Cl. 221—60)

This invention relates to a container and a dispensing device for collapsible tubes of the character generally used for the dispensing of tooth paste, shaving cream and other like and similar substances of a paste-like consistency that are to be exuded through the dispensing head of the container into which the collapsible tube is to be placed.

This invention relates to my present United States application filed in the U. S. Patent Office under date of Nov. 19, 1932, as evidenced by Serial Number 643,434 for Holding and dispensing devices.

My present invention comprises a pair of hinged wall-forming members that are hingedly secured together at one of their ends. The oppositely disposed ends of the pair of side wall members have latches disposed thereupon for securing the hinged members together. Half circular holes are disposed within the free ends of the hinged side wall members and through which the neck of the tube passes. The tube is held therein by the removable head that is threadably secured to the neck of the tube in the usual manner.

An elongated slot is disposed in one side of one of the side wall members. A pressing head is provided for being secured to and moved along the tube. The pressing head comprises a base and a yoke. A shaft is disposed transversely of the yoke and a locking cam is hingedly secured to the shaft and a lever is secured to the cam and rocks the cam into and out of pressing engagement with a shoe that is adjustably secured to the yoke and the shoe is disposed between the cam and the tube so that as pressure is applied to the cam the shoe is placed in locking engagement with the tube and prevents premature movement of the pressing head relative to that of the tube. A plate is hingedly secured to the shoe and a hand lever is secured to the pressing plate. The lever of the cam and the lever of the pressing plate are placed in registry with the elongated slot disposed in one side of one of the hinged closure members and the same are held in alignment by the elongated slot. The levers that are secured to the cam and to the pressure head may be suppressed within the confines of the side walls of the closure for the tube container to limit the projections of the levers extending beyond the side walls of the container when not in active use. A special head is provided for the tube comprising a valve having a slit disposed therein that is placed into and out

of registry with the exuding hole disposed within the head.

The primary object of this invention is to provide a simple and easily operated form of container for tubes having a plastic compound disposed therein. The hinged containers have movable means disposed therein for applying a definite pressing action upon the walls of the container for exuding the contents therefrom. Through the use of the device as herein outlined, practically the entire contents of the tube may be dispensed therefrom in an orderly and efficient manner.

A still further object of my invention consists in providing supporting means for the container that facilitates its being supported upon the wall or within the cabinet ordinarily disposed within the bath room.

And a still further object of my invention consists in providing a tube holder that may be held in one hand and the contents of the tube or partial contents of the tube be exuded from the tube with one hand, leaving the other hand free for holding the brush or other applicator to which the contents of the tube are to be applied.

And a still further object of my invention consists in providing a pressure applicator that may be moved longitudinally of the tube from time to time to provide a pressure applicator for the dispensing of the contents of the tube in an orderly manner and without the use of a reacting element for moving the pressure applicator along the tube.

A still further object of my invention consists in providing a container that may be supported upon the wall or be placed within the traveler's bag, at his option.

With these and incidental objects in view, the invention consists in certain novel features of construction and combination of parts, the essential elements of which are set forth in the appended claims, and a preferred form of embodiment of which is hereinafter shown with reference to the drawing which accompanies and forms a part of this specification.

In the drawing:

Fig. 1 is a perspective side view of the assembled device illustrating the same in an upright position.

Fig. 2 is a plan view of the top end of the device as illustrated in Fig. 1. This is a view of the free ends of the case.

Fig. 3 is a sectional side view of the assembled device. This view illustrates the pressing applicator secured to the tube and illustrates the

pressure plate in position for applying pressure to the tube. This view is taken on line 3—3 of Fig. 2, looking in the direction indicated.

Fig. 4 is a fragmentary sectional plan view of the pressing head adapted to the collapsible tube and disposed within the hinged container. This view is taken on line 4—4 of Fig. 3, looking in the direction indicated.

Fig. 5 is a sectional end view of the container and of the pressing head. This view is taken on line 5—5 of Fig. 3, looking in the direction indicated.

Fig. 6 is a side view of the pressing head and a sectional side view of the hinged container. In this view the pressing head is shown with the respective levers unlatched from the tube and they are shown depressed within the confines of the tube.

Fig. 7 is a fragmentary sectional side view of the free ends of the hinged shell closures. This view is made to illustrate the locking latch for securing the free ends together.

Like reference characters refer to like parts throughout the several views.

I provide a pair of hinged half shell closures 1 and 2. These hinged closures are preferably made semi-circular or elliptical in transverse cross section. The two are hinged together at one end about a common hinge pin 3. A locking latch 4 is secured to the free end of one of the half shell-forming members. The locking latch is made of spring material and a loop 5 passes through the head 6 of one of the half shell members and the loop is then flattened out as illustrated in Fig. 7 to lock one end of the latch relative to one of the half-shell members. A tail 7 is disposed upon the outside of the head 6 to act as a support for the latch. A loop 8 is disposed adjacent the free end 9 of the locking latch and the same normally passes through a receiving hole 10 disposed within the head 11 of the oppositely disposed end of the other half-shell section and when so normally engaged secures the two shell members together.

Best results are to be obtained where two of these locking latches are used as illustrated at 12 and 13 in Fig. 2. One of the locking latches is placed at opposite sides of the transverse center line 14.

I form an elongated slot 15 centrally of the half-shell hinged member 2. This elongated slot runs somewhat less than the full length of the half-shell section member.

The container should be made of a size to fit the collapsible tube 16. These collapsible tubes are made of various sizes to adapt the same for holding different quantities of materials.

Generally speaking, the tooth paste tube is of one size and shaving cream or cold cream tubes are of different sizes and my holder should be made of a size to substantially encompass the filled tube of material to be placed therein.

Half cylindrical holes 17 and 18 are placed in the oppositely disposed faces of the heads 6 and 11 in order to provide a precise locator for the neck 19 of the tube 16. The outer end of the neck 19 is threaded to provide suitable means for removably securing the exuding head 20 thereto. A valve 21 is disposed transversely of the exuding head and a bail or other suitable turning member 22 is secured to the valve 21. An exuding slot 23 is disposed as an outlet through the exuding head and the valve 21 has a like slot disposed therein that is adapted for being placed into and out of registry with the slot 23.

When the two slots are in registry the slot 23 then communicates with the interior of the tube and permits material to be exuded therethrough when abnormal pressure is applied to the body of the collapsible tube.

I provide a pressure assembly within the container. The pressure assembly is not secured directly or indirectly to either one of the half-shell members of the container and the same is adapted to be freely moved in either direction 10 therein.

I provide a yoke 24. The yoke 24 engages the bottom half-shell member at the point of the bends 25 and 26 and the terminal ends 27 and 28 engage the inner surface of the top shell member 2. The yoke is preferably made of spring material. A base 29 is looped about the mid-section of the base 30 of the yoke and the same is fixedly secured thereto. The base is also preferably made of spring material. The upper contour 31 of the base comprises a segment of a circle.

In the placing of the base 29 about the mid-section 30 of the yoke a space 31A should be left between the fixed end 31B of the yoke and 25 the underside of the free end of the base. This provides for greater resiliency to the tongue 31 of the base and prevents a solid contact between the shoe 37 and the base 29 when the cam 35 is used as a clamp for clamping the pressing assembly in place upon the exuded end of the compressible tube.

A shaft 32 runs transversely of the yoke and is fixed into the side walls 33 and 34 of the yoke. A pressure cam 35 is hingedly secured to the shaft 32. A lever 36 is secured to the cam and the lever is used for rocking the cam 35 into and out of clamping engagement. The lever 36 is so positioned as to be placed and moved within the elongated slot 15.

When the lever 36 is in position as illustrated in Fig. 6 the cam is out of contact engagement with the shoe 37. The shoe 37 has projecting ends 38 and 39 that outwardly extend from the central section of the shoe and the same engage the vertical edges of the side walls 33 and 34 of the yoke. A hinge pin 40 is secured to the opposite edge of the shoe to that in which the projections 38 and 39 of the base are disposed and the ends of the shaft 40 and the projections 38 and 39 form a guideway so that the shoe 37 will float up and down between the top 41 of the base and the bottom 42 of the camming surface. When the two are in the position as illustrated in Fig. 6 with the lever depressed, the shoe 37 and the base 41 are spaced apart to permit a free movement of the pressing assembly along the flattened surface 42 of the partially collapsed tube 16. A

pressing plate 43 is hinged about the hinge pin 40 and a hand engaging lever 44 is secured to the free end of the pressing plate 43. The underside 45 of the pressing plate 43 also forms the segment of a circle and the application of pressure to the pressing plate 43 flattens the collapsible tube into a strip along its medial line to thereby exude the plastic material from the tube in an orderly manner and substantially central to that of the exuding slot disposed within the exuding head of the collapsible tube.

The hand lever 44 is also positioned to be moved within the elongated slot 15 and when it is desired to place the container in which the collapsible tube is placed within a bag, the same may be moved toward the base end of the tube

and entirely repressed within the assembly and into the position as illustrated in Fig. 6.

While the form of mechanism herein shown and described is admirably adapted to fulfill the objects primarily stated, it is to be understood that it is not intended to confine the invention to the embodiment herein shown and described, as it is susceptible of embodiment in various forms, all coming within the scope of the claims

10 which follow.

What I claim is:

1. In a device of the class described, the combination of a pair of shell-forming members hinged together upon their one end and means disposed upon their opposite end for latching the shell members together, a pressing device removably disposed within the shell members and adapted to be moved longitudinally within the shell members, means for clamping the pressing device to a collapsible tube and means for applying pressure to the tube and for urging the contents of the tube toward the discharge end of the tube both of said means including clamping levers extending outwardly from the pressing device, a slot disposed in the wall of one of the shell members and the levers of the pressing means being normally disposed within the slot and for being manually manipulated within the slot and for being repressed within the encompassing walls of the shell-forming members.

2. In a device of the class described, the com-

bination of a pair of shell-forming members fixedly secured together upon their one end and means disposed for removably attaching them together upon their other ends, means for fixedly maintaining a tube within the shell members, pressure-applying means having clamping levers secured thereto disposed within and movable within the shell members, means for attaching to and detaching the pressing means from the tube, and means for extending the clamping levers beyond the confines of the shell members and for repressing the same within the confines of the shell-forming members.

3. In a device of the class described, the combination of a pair of shell-forming members fixedly secured together at their one end and means for removably attaching them together at their opposite ends, means for fixedly maintaining a dispensing tube within the shell members, pressure-applying means having clamping levers secured thereto disposed within and movable longitudinally of the shell-forming members on the interior thereof, means for attaching to and detaching the pressing means from the tube, means for extending the clamping levers beyond the confines of the shell members and for repressing the same within the confines of the shell-forming members, and means for locking one of said clamping levers in its extended position.
